UNITED STATES PATENT OFFICE.

LEWIS E. MORRISON, OF NEWARK, NEW JERSEY, ASSIGNOR TO HIMSELF AND
MATTHIAS PLUM, OF NEWARK, NEW JERSEY.

TRIPPING MECHANISM FOR PLATEN-PRESSES.

1,113,676.

Specification of Letters Patent. Patented Oct. 13, 1914.

Application filed February 14, 1913. Serial No. 748,327.

To all whom it may concern:

Be it known that I, LEWIS E. MORRISON, a citizen of the United States of America, and a resident of Newark, Essex county, 5 New Jersey, have invented certain new and useful Improvements in Tripping Mechanisms for Platen-Presses, of which the following is a specification.

This invention relates to improvements in 10 tripping mechanism for platen presses.

More particularly this invention is applicable to platen presses provided with an automatic feed of the type described in my pending application, Serial Number 449,421 15 and provided with an automatic delivery of the type disclosed in the Patent Number 1,025,418.

The object of the invention is to provide 20 a tripping mechanism which shall operate to trip the press when either a sheet fails to reach the platen to be printed, or when a sheet, having been printed, fails to be seized by the delivery grippers.

Other objects will appear as this specification proceeds.

In the drawing illustrating my invention, 25 Figure 1 is a side elevation of a platen press equipped with automatic feed and delivery devices and provided with my tripping mechanism, and Fig. 2 is a diagram of the electrical circuits for operating the different elements in the tripping mechanism.

The press itself comprises a suitable framework 1 in which is pivoted the platen 2 while 3 is the form member pivoted at 4. 35 5 is the main shaft, driven in a well known manner and which carries on both sides of the press a crank disk 6 to which connecting rods 7 are pivoted to oscillate the form member.

The platen is pivoted at 8 and oscillates in a well known manner.

In the following description details are omitted because either the elements referred 45 to are known to the art in general or the specific elements and their operation have been described by me in pending applications and patents which will be referred to as they occur.

50 In front of the platen there is provided an auxiliary frame 9 on both sides of the press. A paper table 10 rests on this frame and supports the paper or other matter 11

to be printed. I employ an automatic sheet separating device for separating the single 55 top sheet from the pile and transfer it to the feed table which feeds the sheet to the platen. The separating device is described and claimed in detail in my pending application Serial Number 449,421 so only a brief 60 description is necessary here.

The numeral 12 represents a suction nozzle carried by an arm 13 which is pivoted at 14 to a large lever 15 pivoted at 16 to the frame. There is a lever 15 on each side of 65 the press. The one on the near side is broken off for the sake of clearness and only the one on the far side or the right side of the press carries the suction nozzle arm 13. The two levers 15 are connected at their 70 lower ends by a rod 17 and are oscillated on their pivots 16 whereby the suction nozzle is operated to pick up a sheet from the pile and transfer it to the feed table. 18, 19 denote elements which assist in the operation 75 of the suction nozzle as set forth in the application 449,421. 19 is the pump pivoted at 20. A hose 21 connects the pump with the suction mechanism at 22.

Suitably pivoted at 23 near the floor are 80 two levers 24, one on each side. Through their pivot at 23 their lower ends are connected and at the top they are connected by the gripper carriage 25 which carries one or more pair of grippers 26. The one lever 85 24 has an arm 27 to which is connected a bent link 28 which is pivoted to the operating rod 7 on the far side of the press, whereby, during the operation of the press the levers 24 are oscillated on their pivot 23. The 90 levers 24 about the rod 17 to operate the grippers toward the platen as shown and the levers 24 also carry a spring 29 the other end of which is secured to the rod 17 on the levers 15, whereby, when the levers 24 are 95 moved to the left the upper ends of the levers 15 are moved to the right. In other words, it will be clear that the grippers and the suction separating mechanism at 12 are operated in opposite directions by the levers 24 which in turn are operated by the rod 28 pivoted on connecting rod 7. The 100 detailed construction and operation of the grippers are described in my Patent, Number 1,025,418.

30 is the feed table which is pivoted at 31

to the frame 9. The feed table is raised and lowered by the oscillations of the platen through the instrumentalities of the rollers 32 oscillating levers 33, pivoted on the 5 frame 9 and upon which the grippers slide and the rollers 34 and cams 35. The detailed construction and operation of the feed table is described in my pending application numbered serially 416,203.

10 36 represents the usual trip lever of the press pivoted at 37 and which operates to trip the form through the well known tripping means 38, 38. In addition to this manually operated tripping mechanism, the press 15 is provided with an automatic trip, described and claimed in my pending application serially numbered 418,021, and the main features of which comprise a contact plate 39 and a pivoted contact 40 both carried by 20 the feed table. On the left side of the press is the usual platen locking cam 41 and the said pivoted contact 40 is operated from the said cam through the levers 42, to 46 inclusive in such a manner that if a sheet fails 25 to be placed on the feed table by the suction means 12, the pivoted contact 40 falls down upon the fixed contact 39 and closes an electrical circuit which includes a magnet 47 in the trip lever 36. When this magnet is en- 30 ergized, the armature pulls down a latch 48 pivoted on the trip lever. The latch engages a lever 49 pivoted at 50 to the connecting rod 7 and as the latter moves to the right, the lever 49 through the latch carries the 35 trip lever along and trips the press as shown. Thus provision has been made for tripping the press when the suction means fail to operate or the sheet is fed by said means into an improper position on the feed table 40. It happens, however, sometimes that after the sheet has been transferred to the platen, it becomes crumpled or otherwise is put into an improper position, so that it 45 cannot be seized by the grippers and delivered but remains on the platen and spoils the succeeding sheets. To overcome this trouble I have devised means whereby when no sheet is seized by the grippers these latter by the closing of the gripper jaws, close an 50 electric circuit which trips not alone the press but also the suction means to prevent further sheets from being fed to the table and from thence to the platen, and thus prevents a number of crumpled sheets from be- 55 ing massed upon the platen and cause injury to the tympan and the form. To this end I have placed upon one of the gripper jaws a properly insulated contact 51, see Fig. 2, and upon the pump 19 there is mounted a 60 magnet 52. The pump is provided with a hole 53 leading to the atmosphere and which is normally covered by a swinging cover 54. A spring 55 on the cover pivot tends to 65 swing the cover to the right in Fig. 2 to un- cover the hole, but is prevented from doing

so by the magnet armature 56 pivoted at 57. When the magnet is energized the armature is raised and the cover 54 is swung by the spring 55 in under the magnet and the hole 53 is uncovered. By referring to Fig. 2 it 70 will be seen that 58 is the battery or source of electrical power and which is connected to the two movable contacts, 51 on the grippers and 40 on the feed table. The battery is also connected to the magnet 52 on the 75 pump and the magnet 47 on the trip lever. The other side of the magnets are ground on the machine indicated by the wires 60. During the operation of the press there are always three sheets separated from the pile. One is in the act of being lifted from the pile by the suction means 12, the second is lying on the feed table and the third is on the platen, and each sheet during its passage through the press must pass between contacts 39 and 40 and be seized by the grippers. Now, if the sheet is not between the contacts 39 and 40 when these are mechanically brought together the press will be tripped as we have seen and the magnet 52 90 will also be energized and the suction means will be tripped too, due to the uncovering of the hole 53. A signal 61 is included in the circuit and when the press trips, the signal operates and the operator will then attend the press, remove the sheet which causes the trouble and the circuit then opens automatically when the contacts 39 and 40 are again separated mechanically. The operator also swings the cover 54 back over the 100 hole 53 and the armature 56 falls in behind the cover. If the grippers cannot seize the sheet, contact is made by the closing of the jaws and again the circuit will be closed and the press tripped. The grippers open automatically when they reach the position shown in Fig. 1.

Thus it will be clear that if for any reason a sheet is misplaced either on the feed table or on the platen, the press and the suction means are tripped to prevent improper printing and the feeding of more sheets on top of those improperly placed. The advantage of tripping the suction means will be apparent when it is considered that if the 110 operator cannot attend to the tripped press at once, the suction means would keep on piling up the sheets on the table and from there to the platen and thus many sheets 115 might be wasted and the form might be 120 spoiled.

Changes in the detailed construction may of course be made within the spirit of the invention and the scope of the appended claims.

I claim:

1. In a printing press the combination of suction means for separating the sheets, a pump for supplying the suction to said means, a platen, mechanism for removing 130

the printed matter from said platen, an electrical circuit having its two normally open terminals supported on said mechanism and devices operable upon the closing of said terminals for rendering said pump inactive.

2. In a printing press the combination of printing means, a sheet separating device including a pump, grippers for delivering the printed sheet from said printing means, 10 a normally open electric circuit having two terminals carried by said grippers and devices operable upon the closing of said terminals for rendering the said pump inactive to trip the said separating means.

3. In a printing press the combination of a sheet separating mechanism including a pump, a magnet on said pump, a normally open electrical circuit, including said magnet, means for closing said circuit to energize the said magnet and means operable by 15 the latter for opening communication between the interior of said pump and the at-

mosphere to render said sheet separating mechanism inactive.

4. In a printing press the combination of 20 a sheet separating mechanism including a pump, a magnet on said pump, a tripping mechanism including a second magnet, a normally open electric circuit including both of said magnets, means for closing said circuit to energize both of said magnets and devices rendered operative when the said magnets are energized for rendering said pump inactive to trip the said sheet separating mechanism and for operating the said tripping mechanism to trip the said press.

Signed at Newark, N. J., this 1st day of February, 1913.
